TRAVERSE CURTAIN ROD

Archie A. Allen, Sturgis, Mich., assignor to Kirsch
Company, Sturgis, Mich.

Application May 22, 1936, Serial No. 81,238

4 Claims. (Cl. 156—20)

This invention relates to traverse curtain rods and particularly to those of the type in which a curtain rod of C-shaped cross section is used as a track for curtain supporting slides and for the concealment of the traverse cords used to actuate the slides. It has particular application to cut to measure rods of C-shaped cross section.

Heretofore it has been the practice to employ in such traverse rods pulleys or sheaves over which the cords pass. These pulleys or sheaves were located adjacent the ends of the rods and the rod was cut away at the bottom to provide a slot through which the operating cords hung so as to be available to be grasped to manipulate the slides and the curtains or draperies attached thereto. Although this type of traverse curtain rod operated satisfactorily, it presented many problems to the manufacturer or dealer because it was necessary to provide and keep in stock a great many sizes and types of rods, fixtures and brackets because it was not possible to use the same rods and brackets for the various window treatments desired by customers. Various sizes of elbows had to be kept in stock and various sizes of pulley sets were required. This made it necessary for the manufacturer, his branches, dealers, decorators, retailers or workrooms to carry in stock several different sizes of the various brackets, elbow sets and pulley sets.

30 The objects of this invention are:

First, to produce a traverse rod and fixtures therefor which eliminate the necessity for manufacturing and stocking the various required sizes and varieties of equipment heretofore necessary.

Second, to provide fixtures which can be used in connection with regular stock curtain rods of C-shaped cross section to make possible the assembly of a traverse curtain rod without the necessity for having special fixtures other than those employed ordinarily in installing curtain rods of this general type.

Third, to provide fixtures for a traverse curtain rod in which a cord separator or guide is employed which is clamped in position on the rod so that the traverse cords may pass out through the slot in the rod and hang down to be reached for manipulation of the traverse equipment.

50 Other objects and advantages pertaining to details and economies of construction and operation will appear from the description to follow. Preferred embodiments of my invention appear in the accompanying drawing, in which:

55 Fig. 1 is a rear elevation view of a curtain rod having embodied therein my invention.

Fig. 2 is a detail sectional view taken on line 2—2 of Figs. 1 and 2.

Fig. 3 is a detail sectional view taken on line 60 3—3 of Fig. 1.

Fig. 4 is a view in section showing my cord separator in position on a rod.

Fig. 5 is a perspective view showing the parts of my improved cord separator in separated relationship.

Fig. 6 is a rear view of the outside plate of my improved cord separator.

Fig. 7 is a detail sectional view taken on line 7—7 of Fig. 1.

Fig. 8 is a top plan view of my invention in place on a curtain rod showing the method of supporting the rod in a standard bracket.

In Figs. 1—8 I illustrate my invention. 1 is a curtain rod of standard type. This rod is a sheet metal rod formed with a C-shaped cross section 15 and having a slot 2 extending the length thereof on the back side. In this specification, when I refer to a rod of C-shaped cross section, it will be appreciated that I refer to rods of this general type and that the rods, instead of being flat or oval as shown, may be round or square, it being essential only that they have a slot in the back as shown and as is common in this type of curtain rod.

The traverse equipment consists of master 25 slides 3 and curtain or drapery supporting slides 4 which are fitted in the slot 2 in the rear of the rod 1 and are provided with apertures 5 for receiving curtain hooks or the like for supporting curtains or drapes. At one end of the rod is a 30 single pulley 6 mounted on an axle 7 fastened to a plate 8 which is of a size to fit within the rod 1 and bridge the slot 2 therein. A screw 9 is screw threaded in a hole 10 in the plate 8 and the head 11 of the screw is of a size to clamp 35 the plate in position, as shown, supporting the pulley in any desired position on a rod.

My improved cord separator and guide is shown at 12 and the traverse cord is shown at 13. This cord extends through an aperture in the cord 40 separator 12 inside of the rod 1 to one of the master slides 3, thence over the pulley 6 back to the other master slide 3 and back through an aperture in the separator and guide 12. Pulling on one branch of the cord 14 moves the slides in 45 one direction and pulling on the other branch 15 moves them in the opposite direction. The cord separator and guide consists of an inner plate 16 and an outer plate 17. These plates are of a size to span the slot 2 and are provided 50 with a screw 18 fitting in a screw threaded opening 19 in the inner plate, so that the plates may be clamped in position across the slots 2 as shown in Figs. 2 and 3. The inner plate 16 is provided with a pair of slots 20 and 21. These 55 slots are disposed in slanting relationship and diverge from one another as shown. The outer plate 17 is provided with apertures 22 and 23 registering with the slots 20 and 21.

Lugs 24 are provided on the inner plate 16 60

and notches or slots 25 are provided on the outer plate 17 to receive the lugs 24 when the cord separator and guide is in position on the curtain rod 1. The slots 20 and 21 slant and diverge from one another and have their edges rounded as shown at 26 to prevent wear on the cord. The inner side of the apertures 22 and 23 are similarly rounded at 27. The slots 20 and 21 are slanting and diverging to provide for clearance for the cord 13.

In Fig. 4, I have shown the cord 13 passing from the inside of the rod through the slots 20 and 21. It will be noted that the lower portion 28 of the cord 13, extending to the left of Fig. 4, passes through the bottom of the slot 21, and the branch 29 of the cord 13 passes through the top of the slot 20 so that the branches 29 and 28 of the cord are disposed one above the other as shown, providing clearance and preventing jamming of the cords inside of the rod. It will be appreciated that if the cord separator and guide 12 were placed at the other end of the rod 1, the cords would take the position shown in the dotted lines in Fig. 4 with the branch 28 of the cord passing through the upper end of the slot 21 and the branch 29 of the cord passing through the bottom of the slot 20. This arrangement makes the cord separator and guide universal and suitable at either end of the traverse 30 rod. Similarly, the pulley 6 and the plate 8 can be put at the opposite end interchangeably, eliminating the necessity for having several different fittings. It will be noted that the rod 1 need not be slotted specially and the cord separator and guide 12 can be positioned anywhere in the slot.

In Fig. 8, I show the rod 1 installed in a bracket 30. The separator and guide 12 is put in place in the rod and the rod is slid into the bracket 40 30 as is common in ordinary curtain rod construction, and the traverse equipment is supported and concealed by the rod and the bracket.

These cord separators and guides can be made of metal, either by die casting or regular casting, or by machining and could be molded of substances such as bakelite if desired.

In the prior art devices where it has been desired to place two sets of traverse equipment on a single rod, it has been necessary to provide a 50 pulley section into which the ends of the cut off rod fit. With my present arrangement, it is possible merely either to slide two cord separators and guides into the center of a rod of any length and use in connection therewith two single pulleys arranged as shown in Fig. 7 at the ends of the rod, and the separators may be placed one at each end of the rod in the manner shown in Fig. 1.

It will be noted that in employing my invention, it is possible to bring the cord out from the inside of the rod through the slot in the rod and to drop it at right angles to the rod, permitting the use of standard rods cut to any desired length without the necessity for bringing the cord out over the rod by running it over a pulley and down through holes in an elbow pulley set or an intermediate pulley set as has been done heretofore.

I wish to claim my invention both broadly and specifically as pointed out in the appended claims.

Having thus described my invention, what I

claim as new and desire to secure by Letters Patent is:

1. A cord separator and guide for a traverse curtain rod construction in which a rod of substantially C-shaped cross section is employed as a track and to conceal the traverse cord, comprising an inside plate to be disposed within the rod and of a width greater than the width of the slot in the rod and having a pair of elongated apertures therein for the passage of the traverse cord, said apertures being disposed in slanting relationship and diverging from one another, an outside plate of greater width than the slot in the rod and having a pair of apertures in register with the elongated apertures in the inside plate, one of said plates having a lug thereon and the other a slot to receive said lug, and means for clamping said plates together, whereby said cord separator and guide is held in position at the slot in said rod by clamping the rod at the edge of the slot between said plates.

2. A cord separator and guide for a traverse curtain rod construction in which a rod of substantially C-shaped cross section is employed as a track and to conceal the traverse cord, comprising an inside plate to be disposed within the rod and of a width greater than the width of the slot in the rod and having a pair of elongated apertures therein for the passage of the traverse cord, said apertures being disposed in slanting relationship and diverging from one another, an outside plate of greater width than the slot in the rod and having a pair of apertures in register with the elongated apertures in the inside plate, and means for clamping said plates together, whereby said cord separator and guide is held in position at the slot in said rod by clamping the rod at the edge of the slot between said plates.

3. A cord separator and guide for a traverse curtain rod construction in which a rod of substantially C-shaped cross section is employed as a track and to conceal the traverse cord, comprising an inside plate to be disposed within the rod and of a width greater than the width of the slot in the rod and having a pair of apertures therein for the passage of the traverse cord, an outside plate of greater width than the slot in the rod and having a pair of apertures in register with the apertures in the inside plate, and means for clamping said plates together, whereby said cord separator and guide is held in position at the slot in said rod by clamping the rod at the edge of the slot between said plates.

4. A cord separator and guide for a traverse curtain rod construction in which a rod of substantially C-shaped cross section is employed as a track and to conceal the traverse cord, comprising an inside plate to be disposed within the rod and of a width greater than the width of the slot in the rod and having a pair of apertures therein for the passage of the traverse cord, an outside plate of greater width than the slot in the rod and having a pair of apertures in register with the apertures in the inside plate, one of said plates having a lug thereon and the other a slot to receive said lug, and means for clamping said plates together, whereby said cord separator and guide is held in position at the slot in said rod by clamping the rod at the edge of the slot between said plates.

ARCHIE A. ALLEN.
